HEAT-TREATING APPARATUS

Howard E. Somes, Detroit, Mich., assignor to
Budd Induction Heating, Inc., Philadelphia, Pa.,
a corporation of Michigan

Original application June 8, 1939, Serial No.
277,996. Divided and this application Septem-
ber 22, 1941, Serial No. 411,851

12 Claims. (Cl. 219—13)

This application is a division of my copending application Serial No. 277,996, filed June 8, 1939, for "Progressive heat-treating apparatus and method," now Patent No. 2,281,333, dated April 28, 1942.

The present invention relates in general to induction heating and in particular to means for the differential heat treatment of interior portions of hollow objects, an important purpose being the hardening or tempering of such portions of objects of a material hardenable by heat treatment such as various ferrous alloys.

A primary object of the invention is the provision of an improved apparatus for heat treating relatively long hollow cylindrical objects, such as cylinder sleeves for internal combustion engines, in increments progressing continuously from end to end, and including an improved induction heat-treating head for use in an induction heat-treating machine, preferably a machine of the type shown and described in my copending application Serial No. 164,320, filed September 17, 1937, for "Induction heat-treating apparatus," now Patent No. 2,281,331, dated April 28, 1942.

A more specific object is the provision of means whereby the localized internal heating of cylinders, such as mentioned above, to or beyond the hardening temperature may be accomplished with minimum clearance without danger of contact between the heating head and the adjacent walls of the workpiece, or danger of seizure of the heating head by the work upon inward local expansion or upsetting of the inner wall portion of the workpiece due to heating.

A further object is the provision of an improvement in the mechanical structure of induction heat-treating heads making possible the construction of heads of relatively small diameter without sacrifice of energy carrying capacity, strength and efficiency, and including efficient means for cooling the same.

While many features of the invention are essentially electrical, certain others are not limited in their application to electrical heating but are applicable to and advantageous with other kinds of heating.

Various other objects and advantages of the invention will become apparent upon a perusal of the following specification and the drawings accompanying the same.

In the drawings:

Fig. 1 is an elevation of the induction heat-treating head and mounting shaft therefor;

Fig. 2 is an elevation in vertical axial section 55

on a large scale of the induction heat-treating head per se and its connection with the mounting shaft;

Fig. 3 is a diagrammatic elevation, partly in section, showing the induction heat-treating head, workpiece and quenching element in cooperative relation.

Referring to the drawings in detail and first to Fig. 1, this shows a complete, replaceable heating tool element comprising in general the induction heat-treating head 10 carried by a hollow tool shaft 11 which latter and the insulated conductor sleeve 12 serve as electrical terminals for the heat-treating head. This assemblage of 10 mounting shaft carrying the conducting sleeve and heat-treating head constitutes a unitary tool element capable of use in a suitable machine assemblage providing suitable means for effecting relative sliding and rotational movement between the tool element and a workpiece with suitable sliding contact means for supplying current to the heat-treating head through the concentric shaft and conducting sleeve, such as the machine assemblage shown and described in my 15 aforesaid application. The tool element is thus interchangeable with other tool elements varying in form according to the work to be done but substantially identical as to the form and proportions of the mounting shaft and conducting 20 sleeve. The heat-treating head 10 comprises an energizing or inducing coil or winding 13 formed of a hollow tubular conductor having its terminals electrically connected one to the tool shaft 11 and one to the insulated conducting sleeve 12, 25 and provided with a hollow cylindrical core 14 of magnetic material having flange-like pole pieces 15 and 16 extending radially outwardly across the top and bottom ends of the coil. At the bottom of the bottom pole piece 16 substantially at the outer edge thereof is formed an annular downwardly and outwardly directed spray nozzle opening 17 in the form of a continuous 30 annular slot for directing an annular spray or jet of quenching fluid downwardly and outwardly 35 from the lower peripheral edge of the bottom pole piece. A second spray nozzle opening 18 also in the form of a continuous annular opening or slot is situated below the nozzle opening 17 and also has its outlet portion directed downwardly and outwardly.

The heating head 10, as a whole, is slightly tapered downwardly so that the outside diameter of the lower core-flange or pole piece 16, is slightly less than that of the upper pole piece of flange 15, their peripheral surfaces, preferably, being

slightly tapered, forming continuations of a common conical surface, so that the mean diameter of the outer peripheral surface of the flange 16 will be smaller than that of the flange 15. For example, in the present embodiment where the workpiece is an engine cylinder sleeve of $4\frac{1}{4}$ inches inside diameter, the diameter of the lower edge of the lower flange 16 is approximately $\frac{1}{8}$ of an inch less than that of the upper edge of the top flange 15, the top flange having a mean clearance sufficient to insure against actual contact with the work. It is this slight taper from top to bottom, that is, a slight taper in a direction opposite to that of the direction of movement of the head relative to the workpiece during operation, which makes possible the use of a minimum clearance between the heat-treating head and the workpiece with assurance against contact with the walls of the workpiece due to inward expansion which reaches its maximum near the trailing edge of the heating element.

The various parts are assembled onto the tool shaft 11 by means of a hollow tubular supporting element 19 threaded at 20 into the lower end of the hollow shaft 11, and carrying at its lower end a shouldered retaining head 21, the retaining head being threaded into the lower end of the supporting element 19 at 22. Mounted on the outside of the shaft 11 is a conducting sleeve 12 insulated from the shaft by an intervening sleeve 23 of insulating material. At its lower end the conducting sleeve 12 is flanged outwardly and abuts a terminal ring element 24 to which it is secured in electrical contact by means of suitable countersunk bolts such as 25, the terminal ring element 24 being insulated from the shaft 11 and the tubular mounting element 19 by the intervening bushing element 26 of insulating material. The ring element 24 is provided with a downward, tubular extension 27 about which is carried an annular mounting flange element 28 insulated from the terminal ring element 24 and its tubular extension by a bushing 29 of insulating material and mechanically secured to the ring element 24 by suitable countersunk bolts such as 30 insulated from the ring element 24 by an insulating bushing 31.

Threaded into the lower end of the mounting flange 28 is a hollow cylindrical core support 32, carrying at its lower end an outwardly extending, core-mounting flange 34. Between this flange and a clamping ring 35 are clamped in place about the core support 32 a series of inwardly tapered radial laminations 36 arranged in close contact to form the hollow cylindrical core element 14, the clamping ring 35 being held in clamping engagement with the top end of the laminations by a suitable clamping nut 37 threaded on to core support 32.

The coil element 13 composed of one or more convolutions of a hollow conductor is wound about the laminated core 36 in the recessed portion between the upper and lower flanges 15 and 16, suitable insulation 38 being provided between the convolutions of the coil and between the coil and the core. The upper and lower terminals of the coil are provided with terminal elements 39 and 40, respectively, which connect with terminal extensions 41 and 42, respectively, extending inwardly through the hollow core 14 and insulated from the latter by means of a sector-shaped insulating plug 43 of the same contour in vertical section as the laminations so as to take the place of the laminations where the terminal extensions pass through the core, as will be clear from Figs.

1 and 2. A conducting extension element 44 extending downwardly from the terminal ring element 24 as part of the latter, establishes electric connection between the sleeve conductor 12 and the terminal extension 41 of the upper end of the inducing coil 13, the terminal extension 41 being threaded into the conducting extension 44. The terminal extension 42 is threaded into the manifold member 45 in electrical contact therewith, so that electrical connection is established between the lower terminal extension 42 and the tool shaft 11, through the manifold member 45 and the tubular support 19. The purpose of the manifold 45 is to effect an even distribution of the quenching fluid from the interior of the hollow supporting element 19 to the spray nozzle. The manifold 45 is held in position on the end of the tubular mounting element 19 by means of the shoulder on the retaining head 21 and the abutting relation between the shoulder 46 within the manifold member and the lower end of the tubular support 19.

The nozzle structure comprises an intermediate nozzle section 47 mounted about the manifold element 45 and provided with an abutment ring portion 53 arranged to be clamped upwardly against the lower end face of the flange 34 on the core support 32 through the intermediation of an adjusting shim or shims 48 and the intervening, inwardly extending flange of a thin spun metal lining element 49 covering the lower surfaces of an annular recess 50 in the lower core flange 16. Also mounted about the manifold element 45 below the intermediate nozzle section 47 is a bottom nozzle ring 51, provided with an abutment ring portion 52 arranged to be clamped against the bottom surface of the abutment ring 53 of the intermediate section through the intermediation of an adjusting shim or shims 54. This clamping of the nozzle sections against each other and against the bottom of the tubular mounting element 19 is effected by means of suitable countersunk cap screws such as the cap screw 55 threaded into the lower end of the tubular core support 32.

Quenching fluid is supplied to the nozzle from a suitable source of supply through the channel within the hollow tool shaft 11 and the tubular supporting element 19 to the interior of the hollow retaining head 21 in which the fluid is distributed through ports 57 in the retaining head and ports 57 in the manifold distributing element 45 to the distributing chamber 58 in the nozzle structure, from which the quenching fluid is ejected downwardly and slightly outwardly of the nozzle through the restricted annular openings 17 and 18. The quenching fluid sprayed through the channel in the tubular supporting element 19 also acts as a coolant for the inducing coil 13 to which it is supplied through a port 59 in the wall of the supporting tube element 19 and the central opening or channel in terminal extension 42 and terminal 40 at the lower end of the coil. The coolant passing upwardly through the coil 13 passes out through the upper terminal of the coil by way of a channel in the terminal element 39 and terminal extension 41 into the outlet chamber 60 from which it passes downwardly and out through the bottom of the nozzle by way of outlet ports, one of which is shown at 61 and of which there may be several spaced around the inner portion of the nozzle between the ports 57. It is to be understood, of course, that the quenching and cooling fluid will be supplied at such a volume and pressure that the back pressure built

up in the chamber 58 due to the restricted flow through the nozzle openings, will be sufficient to force the cooling fluid through the coil at the velocity desired.

Cooperating with the quenching nozzle openings 17 and 18 in the heat-treating head, to maintain the axial extent of the quenching zone substantially constant is a progressively movable bulkhead element in the form of the bulkhead piston 73, as shown in Fig. 3. This piston is arranged to be moved up into the cylindrical workpiece 61 in trailing relation to the heat-treating head by means of a hollow piston rod 74, slideable through a suitable work cylinder 75 within which it is secured to a driving piston 76 for imparting reciprocatory movement to the rod for moving the bulkhead piston into and out of the workpiece. The flared form of the end member 72 at the bottom of the work holder aids in directing the bulkhead piston 73 into the lower end of the workpiece without injury to the piston cap 71. To insure maintenance of a given axial spacing between the piston bulkhead and the bottom or nozzle portion of the heat-treating head, I provide a spacing element 78 carried by the bulkhead piston and arranged to abut the lower end of the heat-treating head. To permit drainage of the quenching liquid out of the space between the heat-treating head and the bulkhead piston down through the hollow piston rod, the spacing element 78 is given the form of an elongated open cage, as shown in Fig. 3. Thus, the extent of the zone of contact of the quenching fluid with the workpiece is maintained substantially constant as the heating and quenching zones are progressed through the workpiece, the waste quenching fluid being maintained isolated from other parts of the workpiece during its passage out of the quenching zone.

A further improved feature of the present heat-treating head is the substantial symmetrical relation of the path of inducing current to the workpiece accomplished through the novel construction of the coil element 13 whereby the end convolutions of the coil are made to lie in a plane at right angles to the axis for substantially a complete convolution which results in the production of a heated zone in the workpiece terminating axially in planes at substantially right angles to the axis of the coil. This is of special utility in combination with the circular quenching jets in the nozzle arranged to direct the quenching fluid against the workpiece in a plane at right angles to the axis in that it brings the plane of the trailing end of the heated zone in the workpiece in parallelism with the plane of the beginning of the quenching zone, thus resulting in uniformity of quenching.

With the jets of quenching fluid directed downwardly from the nozzle openings 17 and 18 as shown and described, they act as shielding diaphragms preventing the quenching fluid from passing upwardly around the heat-treating head, and at the same time, because of their pressure and velocity, permit the existence of some pressure within the quenching chamber between the nozzle and the bulkhead piston, should it seem desirable, which condition may be brought about by suitable regulation of the drain and input to maintain the desired pressure, the velocity of the jets being maintained sufficient to prevent a backing up of the quenching fluid past the heat-treating head. With the structure shown and described the surface being quenched is thus made part of the wall of a channel filled on substan-

tially filled with the cooling fluid or liquid flowing at high speed and, if desired, under high pressure, as distinguished from the usual situation where the cooling fluid is splashed or sprayed against the surface being cooled.

By arrangement of the upper nozzle channel 17 within the lower flange or pole piece 16 to form an annular jet issuing substantially directly from the outer lower edge of the lower pole piece 16, 10 the zone of initial contact of the quenching fluid with the workpiece is brought into extremely close proximity to the trailing end of the heated zone which is the hottest portion of the heated zone. It is further to be pointed out that an 15 advantage of the arrangement whereby cooling fluid is directed through the hollow conductor of the coil 13 from bottom to top, that is in the direction of the progression of travel of the coil relative to the workpiece, is that the part of the 20 coil which is presented to the hottest portion of the progressing heated zone is first to receive the cooling fluid. Also, because the coil is intended to travel upwardly through the workpiece with the result that it is the lower terminal of the 25 coil which is presented to the hottest part of the heated zone, this terminal is the one selected for connection with the tool shaft 11, which latter together with the workpiece, during operation, 30 will lie in electrical contact with a suitable support or frame element not shown, whereby that portion of the coil presented to the hottest part of the work where arcing would ordinarily most likely occur, is maintained at substantially the same potential as the workpiece.

35 In the use of the apparatus above described, for carrying out a preferred method of heat treatment, it being assumed that the tool shaft 11 and work holder are mounted for relative axial and rotary motion in any known or other suitable manner which, for example, may be like that shown in the aforesaid prior application, the tool shaft 11 is moved downwardly to pass the heat-treating head 10 down through the workpiece 61 to a position just below the lower end 40 of the workpiece where the heat-treating head will be surrounded by the lower, low-reluctance extension element 72. In this position, the inducing coil of the heat-treating head is energized from a suitable source of high frequency current supplied to the coil by way of the tool shaft 11 and insulated sleeve 12 through means of suitable contact brush elements which may be of any known or other suitable form, for example, that shown in the aforesaid application. 45 The path of the energizing current may be traced from the tool shaft 11, through tubular supporting element 19, terminal extension 42, terminal element 40, lower end of inducing coil 13, through the inducing coil to the upper terminal element 39, terminal extension 41, conducting extension 44, conducting flange 24, back to the source by 50 way of the insulated conducting sleeve 12.

Immediately upon energization of the inducing coil, the heat-treating head is moved upwardly and out of the top end of the workpiece 61 preferably at a uniform rate of travel, the energizing current being cut off after the inducing coil passes upwardly out of operative relation with the workpiece. Preferably, the energizing current is cut off before the inducing coil leaves the upper low reluctance extension element, so as to prevent complete removal of the coil from the surrounding medium of low reluctance and consequently prevent sudden reduction of the inductive reactance of the coil element. Thus, in 55

known manner, heating currents are generated in the workpiece occupying a field in proximity to the heat-treating head which field of current occupancy and the resulting heated zone is progressed upwardly through the workpiece with the upward movement of the heat-treating head, the trailing end of the heated zone being the hottest at any one moment due to its relatively longer exposure to the influence of the heat-treating head.

Also upon energization of the inducing coil or slightly in advance thereof cooling and quenching fluid is forced down through the hollow tool shaft 11 and hollow supporting element 19 from any suitable source of supply, not shown. The cooling fluid thus forced downwardly through the hollow supporting element 19, passes on through lateral ports 56 in the hollow retaining head 21 and distributing ports 57 in the manifold element 45 into the nozzle chamber 58 and out through the circular nozzle openings 16 and 18 from whence it is forced downwardly and outwardly in two continuous curtains of fluid. Back pressure, developed due to the restricted flow through the nozzle openings, causes the cooling fluid also to flow upwardly through the inducing coil by way of port 59 in the wall of the tubular supporting element 19 near the lower end, and the central channels in the terminal extension 42 and terminal element 40, leaving the coil through the central channels of the terminal element 39 and extension 41 from whence the cooling fluid flows downwardly and out through the bottom of the nozzle by way of drain ports, one of which is shown at 61' (Fig. 2).

Immediately, the lower peripheral edge of the core extension 16 reaches the lower edge of the workpiece, at which moment the lower end of the workpiece is about at its highest temperature, the jet of cooling fluid issuing from the upper nozzle opening 17 contacts with said portion of the workpiece to immediately initiate the quenching of the latter. This quenching of the inner surface of the workpiece continues as the heat-treating head moves upwardly, the quenching effect of the jet from the nozzle opening 17 being augmented by that from the opening 18. As the heat-treating head moves upwardly through the work, it is followed by the bulkhead piston element 73 whose entrance into the workpiece is guided by the outwardly flared lower end extension 72 in the work holder, the bulkhead piston being maintained a definite distance below the heat-treating head by abutment of the spacing element 76 against the bottom of the heat-treating head. Thus, the axial length of the quenching zone is maintained at a given maximum. This progressive quenching operation is continued until and after the heat-treating head has passed beyond the upper end of the workpiece and until after the bulkhead piston reaches the top of the workpiece and energizing current has been turned off. Concurrently with the quenching operation the excess quenching fluid passes downwardly through the open spacing element 78 and the hollow piston rod 74 to a suitable waste or drain connection, not shown. Also, as previously described, the jets of quenching fluid especially the uppermost jet, because of its downward direction and high velocity operates to prevent quenching fluid from passing upwardly around the heat-treating head, and even may be maintained with sufficient pressure and velocity to permit the existence of some pressure within the quenching chamber between the nozzle and the bulkhead

piston. High pressure is desirable not only because it increases the rate of interchange of quenching fluid in contact with the surface being quenched, but also increases the heat absorbing qualities of the quenching fluid.

It is to be understood that in the use of the invention herein disclosed, either the heat-treating element or the workpiece, or both may be moved to effect the required relative movement between them, and that the mere mechanical inversion necessary to change from one such form of relative movement to the other falls within the spirit of the invention and is intended to be covered by those of the appended claims specifying either of such forms of movement, in accordance with the doctrine of equivalents.

While I have thus herein shown and described a specific embodiment and useful application of my invention for the sake of disclosure, it is to be understood that the invention is not limited to such specific embodiment and mode of application, but contemplates all such variants and modifications thereof as fall fairly within the scope of the appended claims.

25. What is claimed is:

1. In combination an induction heat-treating head comprising a hollow cylindrical core support, a hollow cylindrical radially laminated core mounted on said support, a flange carried by the support near the longitudinally outer end for engagement with the longitudinally outer end of the core, a clamping nut threaded onto the support longitudinally inward of the core for clamping the core against the said flange, a tubular conductor winding for the core having terminals extending radially inward to the interior of the support, a mounting flange threaded onto the longitudinally inner end of the core support, a terminal ring element secured to the mounting flange and insulated therefrom, a conducting extension element connecting the terminal ring with the longitudinally inner terminal of the tubular winding through the interior of the support, a hollow supporting shaft for the coil and core support extending through the core support and electrically connected with the longitudinally outer terminal of the coil, and a conducting sleeve element mounted on said supporting shaft, insulated therefrom and secured to said terminal ring in electrical connection therewith.

2. An induction heat-treating head comprising, in combination, a hollow generally cylindrical member, an inducing coil surrounding said member, said member having an opening through the cylindrical wall thereof and said coil having terminal ends extending through said opening to the interior of said member, an electrically conductive mandrel separate from and disposed within said member and being electrically connected with one of said terminal ends, an electrically conductive member surrounding and electrically insulated from said mandrel and electrically connected with the other of said terminal ends, and means insulating said electrically conductive member from said cylindrical member.

3. An induction heat-treating head comprising, in combination, an electrically conductive mandrel, an electrically conductive sleeve surrounding said mandrel and being insulated therefrom, an annular member surrounding said sleeve and being secured thereto and insulated therefrom, a tubular coil support carried by said annular member in surrounding relation with respect to said mandrel, an inducing coil carried by said support, said coil having terminal ends

extending through the wall of said support, one of said terminal ends being electrically connected with said mandrel, and means within said support electrically connecting said sleeve with the other of said coil ends.

4. In an induction heat-treating head having a central electrically conductive mandrel, an electrically conductive sleeve surrounding said mandrel, a sleeve of insulating material between said sleeve and mandrel and being axially slidably relative to one of said sleeve and mandrel, tubular means connected with said sleeve and surrounding said mandrel in circumferentially spaced relation, an inducing coil carried by said tubular means and having terminal ends extending through the wall thereof, one of said terminal ends being electrically connected with said sleeve and the other of said terminal ends having an axially slidably electrical connection with said mandrel, said sleeve, tubular means and coil including said terminal ends being axially movable as a unitary assembly for assembly to and disassembly from said mandrel, and removable means for holding said unitary assembly on said mandrel.

5. In an induction heat-treating head, a pair of spaced coaxial tubular conductors, means insulating said conductors from each other, an inducing coil having one of its terminal ends electrically connected with one of said conductors and the other of its terminal ends connected with the other of said conductors, and a supporting arbor, one of said conductors being rigidly secured to said arbor in electrical contact therewith and the other of said tubular conductors being in surrounding relation with respect to said arbor and being electrically insulated therefrom.

6. In an induction heat-treating head, a pair of spaced coaxial tubular conductors, means insulating said conductors from each other, an inducing coil having one of its terminal ends electrically connected with one of said conductors and the other of its terminal ends connected with the other of said conductors, and a supporting arbor, one of said conductors being rigidly secured to said arbor in electrical contact therewith and the other of said tubular conductors being in surrounding relation with respect to said arbor and being electrically insulated therefrom, said inducing coil being hollow to conduct cooling fluid therethrough and said arbor and said one conductor having communicating fluid passages in communication with the interior of said coil to conduct cooling fluid to said coil.

7. In an induction heat-treating head, a tubular member of electrically conductive material, means surrounding said tubular member in circumferentially spaced relation and forming a chamber therewith, an inducing coil surrounding said means and having end terminals at least one of which extends radially through the wall of said means, an electrically conductive sleeve surrounding at least a portion of the body and end of said tubular member in electrical contact therewith and having an electrical connection with said one terminal, and means for clamping said sleeve to said tubular member.

8. In an induction heat-treating head, a tubular member of electrically conductive material, means surrounding said tubular member in circumferentially spaced relation and forming a chamber therewith, an inducing coil surrounding said means and having end terminals at least one of which extends radially through the wall

of said means, an electrically conductive sleeve surrounding at least a portion of the body and end of said tubular member in electrical contact therewith and having an electrical connection

5 with said one terminal, and means for clamping said sleeve to said tubular member, said coil having a passageway therethrough communicating through said one connection with the interior of said tubular member for receiving cooling fluid therefrom and communicating through the other of its terminals with said chamber to discharge cooling fluid thereto.

9. In an induction heat-treating head, a tubular member of electrically conductive material, means surrounding said tubular member in circumferentially spaced relation and forming a chamber therewith, an inducing coil surrounding said means and having end terminals at least one of which extends radially through the wall of said means, an electrically conductive sleeve surrounding the end of said tubular member in electrical contact therewith and having an electrical connection with said one terminal, and means for clamping said sleeve to said tubular member, said head including a tubular conductor surrounding and insulated from said tubular member and said means and being in electrical connection with the other of said coil terminals.

10. In an induction heating apparatus for longitudinally progressively heating a circumferential surface of an elongated cylindrical article throughout the circumferential extent thereof, a cylindrical induction heating element having coaxial leading and trailing ends and arranged to be positioned in close proximity to the circumferential surface to be heated with each of its longitudinal increments uniformly circumferentially spaced from such surface with substantially minimum clearance, said trailing end being of sufficiently less diameter than said leading end to substantially maintain said uniform circumferential clearance upon expansion of the portion of the circumferential surface adjacent said trailing end when heated.

11. An induction heating head for longitudinally progressively heating a circumferential surface of an elongated cylindrical article throughout the circumferential extent thereof, comprising a heating coil and a core of magnetic material therefor, said core having coaxial cylindrical end portions extending radially across the ends of said coil, one of said portions constituting a leading end and the other portion constituting a trailing end, said heating head being arranged to be positioned adjacent the circumferential surface to be heated with each longitudinal increment of each of said end portions arranged to have a substantially minimum, uniformly circumferential clearance with such surface, said trailing end portion being of less diameter than said leading end to compensate for expansion toward the same of the circumferential surface to be heated, the respective ends of said coil adjacent said end portions being of no greater diameter than said end portions.

12. An induction heating head for longitudinally progressively heating a circumferential surface of an elongated cylindrical article throughout the circumferential extent thereof, comprising a heating coil and a core of magnetic material therefor, said core having coaxial cylindrical end portions extending radially across the ends 70 of said coil, one of said portions constituting a

leading end and the other portion constituting a trailing end, said heating head being arranged to be positioned adjacent the circumferential surface to be heated with each longitudinal increment of each of said end portions arranged to have a substantially minimum, uniformly circumferential clearance with such surface, the circumferential surfaces of said end portions tapering substantially uniformly from the axially outermost edge of said leading end portion to 10

the axially outermost edge of said trailing edge portion to effect a clearance with the circumferential surface to be heated greater at said trailing end than at said leading end whereby to compensate for expansion of the circumferential surface undergoing heating toward said end portions, said coil being arranged to have a clearance with such surface at least as great as said end portions.

HOWARD E. SOMES.
